UNITED STATES PATENT OFFICE.

JOHN H. OSTER, OF CLEVELAND, OHIO, ASSIGNOR TO ARTHUR S. NEWMAN, OF CLEVELAND, OHIO.

DESIGN FOR A CUFF-BUTTON.

59,372.

Specification for Design.

Patented Oct. 11, 1921.

Application filed January 14, 1920. Serial No. 351,487. Term of patent 3½ years.

To all whom it may concern:

Be it known that I, JOHN H. OSTER, a citizen of the United States, residing at Cleveland, in the county of Cuyahoga, and State of Ohio, have invented a new, original, and ornamental Design for Cuff-Buttons, of which the following is a specification, reference being had to the accompanying drawings, forming a part hereof.

I claim:—

The ornamental design for a cuff button as shown.

JOHN H. OSTER.
